UNITED STATES PATENT OFFICE

CONWAY, BARON VON GIRSEWALD, HANS WEIDMANN, AND GERHARD ROESNER, OF FRANKFORT-ON-THE-MAIN, GERMANY, ASSIGNEES TO AMERICAN LURGI CORPORATION, OF NEW YORK, N. Y., A CORPORATION OF NEW YORK

PROCESS FOR THE PRODUCTION OF ALKALI PHOSPHATES FROM METAL PHOSPHORUS COMPOUNDS

No Drawing. Application filed January 21, 1931, Serial No. 510,320, and in Germany January 27, 1930.

This invention relates to a process for the production of alkali phosphates from metal phosphorus compounds.

It is known to convert metal phosphorus compounds, especially iron phosphide, into alkali phosphates by decomposition with alkali sulphates, at elevated temperatures. Thus for example it has been proposed to heat a mixture of a ferro phosphorus containing 12.5% of phosphorus and corresponding to the formula Fe_3P , to a red heat with sodium sulphate in a rotary furnace; the reaction proceeding in accordance with the following equation:

It has been shown that when decomposing high percentage phosphorus alloys the quantity of metal added in conjunction with the phosphorus is not sufficient to combine with all the sulphur set free from the alkali sulphate and that in this case the sulphur escapes in the form of sulphur dioxide, for example according to the equation:

The removal of large quantities of sulphur dioxide produced in this manner on a large scale is a matter of the greatest difficulty, if there is no possibility of utilizing it in situ. If for example it should be desired to dilute the waste gases with air to such an extent that they can be allowed to escape into the atmosphere, the quantity of air required would be so large as to render the economy of the whole process very doubtful.

It has now been found in accordance with the present invention that it is possible to avoid this drawback by allowing the reaction between the metal phosphorus alloy and the alkali sulphate to take place in the presence of substances which are adapted to convert the sulphur set free during the decomposition, so far as it has not already combined with the metal added in the form of phosphorus alloy, into a form in which it is prevented from being oxidized to form SO_2 , especially in the presence of the said substances

in an amount sufficient to combine with practically all this sulphur. Suitable substances to be added are chiefly metals of the most diverse kinds, and also non-metallic, inorganic or organic reducing agents, such as for example, carbon or coal in any form, or substances containing carbon or coal; the reaction proceeding in the presence of coal for example, in the following manner

The present process furthermore offers the advantage that it is possible completely to combine all the sulphur contained in the alkali sulphate—when employing for example iron or coal or the like as the reducing additional substance,—with the iron present in the charge in the form of iron sulphide and to render said sulphur useful. When employing coal the content of sulphur in the iron sulphide can be increased in this manner to about 29%, whilst in the absence of coal a sulphur content up to about 23% only can be attained in the iron sulphide.

The herein-described method of working is applicable with particular advantage to a process for the decomposition of metal phosphorus alloys,—especially high percentage metal phosphorus alloys—with alkali sulphates, according to which the metal phosphorus alloy is introduced into the fused alkali sulphate, as well as in the case of another process according to which the components of the reaction are heated by electrical resistance heating.

Example

2 tons of iron phosphide containing 22% of phosphorus are melted down with 3 tons of sodium sulphate in admixture with 230 kgs. of finely ground coal in an electrical resistance furnace. No losses of sulphur due to the formation of sulphur dioxide occur in this fusion process. The melt is lixiviated in known manner and iron sulphide filtered off has a dry content of 28% of sulphur and 0.2% of phosphorus.

We claim:

1. A process for the production of alkali

- phosphates which comprises decomposing at elevated temperatures in the presence of a reducing agent an alkali sulphate with a metal phosphorus alloy, the metal content of which is not sufficient as such to combine with all the sulphur of the alkali sulphate, the reducing agent being present in an amount sufficient to protect practically all the sulphur from oxidation to SO_2 .
- 10 2. A process for the production of alkali phosphates which comprises decomposing at elevated temperatures in the presence of a reducing agent an alkali sulphate with ferro-phosphorus, the iron content of which is not sufficient as such to combine with all the sulphur of the alkali sulphate, the reducing agent being present in an amount sufficient to protect practically all the sulphur from oxidation to SO_2 .
- 15 3. A process for the production of sodium phosphate which comprises decomposing at elevated temperatures in the presence of a reducing agent sodium sulfate with ferro-phosphorus, the iron content of which is not sufficient as such to combine with all the sulphur of the sodium sulphate, the reducing agent being present in an amount sufficient to protect practically all the sulphur from oxidation to SO_2 .
- 20 4. A process for the production of alkali phosphates which comprises decomposing at elevated temperatures in the presence of a carbonaceous reducing agent an alkali sulphate with a metal phosphorus alloy, the metal content of which is not sufficient as such to combine with all the sulphur of the alkali sulphate, the reducing agent being present in an amount sufficient to protect practically all the sulphur from oxidation to SO_2 .
- 25 5. A process for the production of alkali phosphates which comprises decomposing at elevated temperatures in the presence of coal an alkali sulphate with a metal phosphorus alloy, the metal content of which is not sufficient as such to combine with all the sulphur of the alkali sulphate, the coal being present in an amount sufficient to protect practically all the sulphur from oxidation to SO_2 .
- 30 6. A process for the production of alkali phosphates which comprises decomposing at elevated temperatures in the presence of a metal an alkali sulphate with a metal phosphorus alloy, the metal content of which is not sufficient as such to combine with all the sulphur of the alkali sulphate, the metal being added in an amount sufficient to protect practically all the sulphur from oxidation to SO_2 .
- 35 7. A process for the production of alkali phosphates, which comprises melting down an alkali sulphate together with a metal phosphorus alloy, the metal content of which is not sufficient as such to combine with all the sulphur of the alkali sulphate, and together with a carbonaceous substance in a sufficient amount to protect practically all the sulphur from oxidation to SO_2 .
- 40 8. A process for the production of alkali phosphates, which comprises melting down an alkali sulphate together with ferrophosphorus, the iron content of which is not sufficient as such to combine with all the sulphur of the alkali sulphate, and together with coal in a sufficient amount to protect practically all the sulphur from oxidation to SO_2 .
- 45 9. A process for the production of alkali phosphates, which comprises melting down in an electric furnace an alkali sulphate together with ferrophosphorus, the iron content of which is not sufficient as such to combine with all the sulphur of the alkali sulphate, and together with carbon in a sufficient amount to protect practically all the sulphur from oxidation to SO_2 .
- 50 In testimony whereof, we affix our signatures.
